MOP HOLDER

Conrad Fatland, Chicago, Ill.

Application March 21, 1951, Serial No. 216,691

4 Claims. (Cl. 15—147)

1

This invention relates to an improvement in that type of mop head wherein the frame is composed of two parts pivotally related to each other so that when the two parts are folded toward each other two facing pockets of a very common type of mop swatch may be easily slipped on and then tightly related to the head by pivoting the two parts into a single plane.

The head of this type of mop swatch assumes many configurations, but a popular one consists of two inwardly directed U-shaped elements pivotally related at their ends so that they may be folded toward each other. In this latter position, a pocket of a double pocket mop swatch may be slipped over each of the U-shaped members and when they are pivoted back into a single plane under the pressure of a spring, the two members fully and firmly seat themselves in the pockets and hold the mop in extended position.

The present invention seeks to provide a simplified arrangement of the two pivoted components of the head of this type of mop, the feature being that the two components may be readily moved from folded position to extended position or vice versa, and yet they themselves will hold themselves in either position without manual assistance.

The new result obtained resides in the fact that a woman can use both hands in slipping the mop pockets onto the two components of the mop frame, whereas in present constructions, she must use one hand to hold the folded components against the action of a spring while trying to insert two pockets over the two components of the head.

Applicant seeks to attain this end by a simple construction which utilizes a minimum weight of metal and requires a minimum of tooling and assembling.

These and such other objects as may herein-after appear are attained in the embodiment of the invention shown in the accompanying drawings wherein:

Fig. 1 is a plan view of applicant's mop head with a double pocket swatch mounted thereon;

Fig. 2 is a view from the under side of applicant's mop head, with one portion of the head partially folded toward the other;

Fig. 3 is a side view taken on the line 3—3 of Fig. 2; and

Figs. 4 and 5 are side and end views of a suggested head construction illustrating how a similar bail action can be obtained by somewhat different cam surfaces.

Continuing to refer to the drawings, a plate

2

10 has its forward and rearward edges bent downwardly and inwardly to form facing channels 12 and 14. A pair of upright brackets 16 and 18 are riveted to the top of the plate 10 so that their upright portions are in flush engagement with each other. A handle 20 has its lower end slotted and seated over the brackets 16 and 18. A pin 22, wedged at each end, through both portions of the handle and the brackets, provides a pivoted connection between the handle and the head.

Referring to Fig. 2, the head or plate 10 supports two oppositely disposed similar flat, frame members, 24 and 26, which may best be described as elastic wire bails, each having a set urging the arms outwardly from a parallel position. Two holes are punched in each channel and the aligned, oppositely directed end lugs of the bail 26 seat in two aligned holes and are rigidly held by the fully rolled edges of the plate at points 28.

The other bail or frame member 24 is similarly seated in the other two, oppositely aligned holes, but here the wall of the channel forming flange has been cut back along the line 30 so as to form a cam edge. This cam edge, referring to Figs. 2 and 3, starts at about 90° from the surface of the plate 10 and along a substantially straight line reaches a point about 180° from the plate. When the bail 24 is pivoted out of the plane of the head, the head and the bail must be worked against each other with some force until the arms 32 and 34 have been sprung inwardly sufficiently to clear the shoulders 36 and 38. These two shoulders act as detents holding the arms 32 and 34 in the plane of the mop head. Until the points 36 and 38 have been cleared, the bail 24 will snap back into the plane of the head. Having moved a short distance beyond the shoulders 36 and 38, the bail may be further pivoted easily and it will hold whatever position it is in when stopped. These shoulders 36 and 38 provide additional means for seating the arms 32 and 34 in the channels. If the shoulders are omitted with the camming edge starting 90 degrees from the surface of the plate 10, the bail arms still must be snapped out of position and they snap back into the channels after they have moved to the left of a point approximately that of the lead line 30.

The type of opposite double pocket mop swatch 40 shown in Fig. 1 is quickly mounted by folding the bail 24, referring to Fig. 2, into the dash-dot position 42. As soon as each bail has entered its associated pocket for a short distance,

the user commences to pivot the bail 24 back to its extended or operating position and in so doing this automatically forces both bails into the extremities of their associated pockets.

The construction has two major advantages. Firstly, the user need not hold the bails in folded position with one hand while attempting to insert them into the double pockets with the other, as is common today in this type of mop wherein a continuously acting spring urges the bails into extended position. A user of applicant's mop can set the two bails in such folded relation as desired and then use both hands to position the swatch pockets over the bails.

The second advantage of this construction resides in the fact that the entire head is simple to make and simple to assemble, while nevertheless forming a very firm mop head with respect to both the mop swatch and the handle attached to the head. The head or plate 10 can be stamped flat from a single die with the cam edge 30 therein. The brackets 16 and 18 are identical and are readily riveted into place. The rolling operation is easily performed.

Referring to Figs. 2 and 3, dimples 44 in the plate 10 prevent the end lugs 46 and 48 of the bail 24 from being disassembled from the base. This may alternatively be done by swedging the ends of the lugs 46 and 48 so as to have one dimension greater than the diameter of the holes in the channels.

There are other ways of constructing a camming surface which will perform the same function as the edges 30. The important thing is that these edges squeeze the two arms 32 and 34 gradually as the bail 24 is moved out of the plane of the mop head and toward the other portion of the head. Referring to Fig. 2, the friction between the bail arms 32 and 34, and the cam surfaces must exceed the tendency of these elastic arms to spread outwardly by sliding along the cam surfaces. Additionally, the detent action performed by the shoulders 36 and 38 could be otherwise attained.

Thus, in Figs. 4 and 5, applicant shows a flat plate 10' wherein the bail 24' has its outwardly directed end lugs 43 pivotally mounted in a vertical side wall 50. This plate is a little longer than that shown in Fig. 2 and has its end 52 bent upwardly and back as shown in Fig. 5. This end member has cut-out portions 54 and 56. The wall 58 performs the same function as the edge 30 in the embodiment shown in Fig. 2. The shoulder 60 performs the same function as the shoulder 36 in Fig. 2.

So long as bail 26 is fixed with relation to the plate 10, it is necessary to bring the bail 24 to position 42 in order to mount the swatch because the distance between the ends of the bails in folded position must not exceed the distance between the pocket openings, see Fig. 1.

Having thus described his invention, applicant claims:

1. A mop head for holding a double pocket

swatch comprising a head, a first flat frame mounted on one side of said head, a second flat frame pivotally mounted on the opposite side of said head so that it may be swung into and out of the plane of the first frame, a cam on the head with its edge gradually but increasingly penetrating the path of the second flat frame when the latter is swung from the plane of the first frame, whereby as the second frame is swung away from the plane of the first frame, the second frame more tightly frictionally engages the cam edge.

2. A mop head for holding a double pocket swatch comprising a head, a first flat frame mounted on one side of said head, a U-shaped elastic spring set bail pivotally mounted by the ends of its arms on said head and having a normal position in the plane of the first flat frame, and a cam on the head with its edge gradually but increasingly penetrating the path of one of the bail arms when the bail is swung from its normal position, whereby as the bail is swung away from the plane of the first frame, the arm is more tightly, frictionally held against the cam edge.

3. A mop head for holding a double pocket swatch comprising a flat plate, one edge of said plate having a 90° roll at one end and a 180° roll near the other end, the edge of the plate connecting the two ends of the roll being along a substantially straight line and constituting a cam, a similar roll on the opposite side of the plate, the two rolls forming facing channels, aligned holes through said channels, an elastic U-shaped bail having its ends seated in said holes with its arms in that end of the channels having the 90° roll, and a complementary U-shaped frame rigidly mounted in the other end of said channels.

4. A mop for holding a double pocket swatch comprising a flat plate, a handle mounted thereon, a roll in each of two opposite edges of said plate, the rolls being on an arc sufficiently large to form two facing channels, the outer edge of each channel extending from a point at one end about 90° from the surface of the flat plate and extending gradually to a point about 180° from said plate, a U-shaped bail rigidly mounted by its arms in the second end of the channels, and a U-shaped elastic bail pivotally mounted by its arms in the channel so that its arms will seat in the facing channels and extend beyond the end having the 90° roll therein.

CONRAD FATLAND.
